Primary Examiner — Cynthia Ramirez*Assistant Examiner* — Michael A Maharajh(74) *Attorney, Agent, or Firm* — Vedder Price P.C.(57) **CLAIM**

The ornamental design for a massage roller assembly, as shown and described.

DESCRIPTION

FIG. 1 is a top perspective view of a massage roller assembly showing my new design;

FIG. 2 is a bottom perspective view thereof;

FIG. 3 is a right elevational view thereof;

FIG. 4 is a top plan view thereof;

FIG. 5 is a bottom plan view thereof; and,

FIG. 6 is a front elevational view thereof.

The broken lines in the drawings are for the purpose of illustrating portions of the massage roller assembly which form no part of the claimed design.

1 Claim, 6 Drawing Sheets# US D938,605 S
